UNITED STATES PATENT OFFICE.

OSCAR V. WOOD, OF FOSTORIA, OHIO.

SIGNAL-TORCH.

SPECIFICATION forming part of Letters Patent No. 644,750, dated March 6, 1900.

Application filed June 30, 1899. Serial No. 722,464. (No model.)

To all whom it may concern:

Be it known that I, OSCAR V. WOOD, a citizen of the United States, residing at Fostoria, in the county of Seneca and State of Ohio, have invented a new and useful Signal-Torch, of which the following is a specification.

This invention relates to signal-torches and similar lights which embody a casing containing inflammable material and a closure-cap adapted to ignite the inflammable material by quickly withdrawing said cap from the casing.

The object of the present invention is to provide improved means whereby the cap is maintained in its proper normal position and also forms a guide for the cap when the latter is being withdrawn from the casing, so that a positive ignition of the inflammable material is insured.

To these ends the present invention consists in the combination and arrangement of parts, as will be hereinafter more fully described, shown in the accompanying drawings, and particularly pointed out in the appended claims, it being understood that changes in the form, proportion, size, and the minor details of construction may be made within the scope of the appended claims without departing from the spirit or sacrificing any of the advantages of the present invention.

In the drawings, Figure 1 is a side elevation of a signal-torch constructed in accordance with the present invention. Fig. 2 is a longitudinal sectional view thereof. Fig. 3 is a perspective view of the torch having the cap and handle removed. Fig. 4 is a transverse sectional view taken on the line $x-x$ of Fig. 2.

Corresponding parts in the several figures of the drawings are designated by like characters of reference.

Referring to the accompanying drawings, 1 designates the casing of the torch, which is formed from paper or other light and cheap material, having the form of a tube and adapted to contain the inflammable material 2. This tubular casing is open at both ends and has a closure-plug 3 fitted to the inner or lower terminal thereof. Fitted centrally to this plug and extending longitudinally beyond the adjacent end of the casing is a pointed metallic stem or shank 4, and housing said shank is a

handle 5, whereby the torch may be held in the hand of the operator. Should it not be desired to hold the torch in the hand, the handle 5 may be removed, so that the pointed stem or shank 4 may be stuck into the ground or other suitable support.

As best illustrated in Fig. 2, it will be seen that the inflammable material is effectively held within the casing by means of a wad 6, fitted within the outer open end of the casing and resting upon the surface of said material. The upper peripheral edge of the casing is bent or crimped inward, forming an inner annular bead or shoulder 7, engaging the outer face of the wad and firmly holding the latter in position.

In the outer side of the casing 1 there is provided a pair of diametrically-opposite and longitudinal grooves 8, which extend nearly the entire length of the casing and open outward through the outer or wad end of the casing. At their outer ends each groove terminates in a slot 9, which communicates with the interior of the casing at a point within the wad 6. Embedded within the inflammable material is a pair of matches 10, having their heads 11 projecting through the respective slots 9 and received within the adjacent grooves 8. It will be understood that the grooves 8 are deep enough to receive the heads of the matches therein and within the outer periphery of the casing, so that the matches are prevented from being accidentally ignited.

The means for igniting the matches comprises a tubular cap 12, which fits snugly the casing 1 and rests upon the outer end thereof, so as to effectually protect the inflammable material and also the heads of the matches. This cap is also formed of light material similar to that of the casing and is provided upon its inner side with a pair of diametrically-opposite and longitudinal ribs 13, which extend from the inner open end of the cap to a point about midway of the length thereof. It is preferable to form the ribs 13 by impressing grooves 14 in the outer face of the cap, as this is the simplest and cheapest method, although the ribs may be formed in any other desired manner. Each rib 13 is provided with a suitable roughened or friction surface 15, and as said ribs terminate short of the outer end of

the cap the matches are prevented from becoming accidentally ignited by a slight movement of the cap.

The casing being filled with the inflammable material, the cap is slipped upon the open end thereof prior to the application of the plug 16 to the outer end of the cap, so that the latter may be forced far enough upon the casing to expose the slots 9 thereof. Then the matches 10 are embedded in the inflammable material, the wad 6 forced within the casing, and finally the outer edge of the latter is crimped upon the wad, as hereinbefore described. After the matches have thus been secured in place 15 the cap is partly withdrawn from the casing, so that the plug 16 may be fitted into the outer end of the cap and thereby effectually close the outer end of the casing. It will of course be understood that the ribs 13 are alined with 20 the grooves 8 in the casing, so as to prevent accidental axial movement of the cap.

To ignite the matches, it is simply necessary to quickly withdraw the cap from the casing whereby the roughened or friction surfaces 25 of the ribs 13 will engage the match-heads, thereby lighting the same and igniting the inflammable material. As the ribs fit within the respective grooves 8 and the latter extend to the outer end of the casing, the cap 30 is guided in its movement so that the proper engagement of the ribs with the match-heads is positively insured.

It will be noted that the matches are prevented from being displaced by the frictional 35 engagement of the cap by means of the wad 6, and the latter is effectually held in place by crimping the outer edge of the casing, as hereinbefore described.

What I claim is—

- 40 1. In a signal-torch, the combination with a casing, containing an inflammable material, and an igniting device embedded in said inflammable material and projecting beyond a side of the casing, of a cap slidably fitted upon the casing, and provided upon its inner side with a fixed roughened or friction surface, and means for preventing accidental axial turning of the cap upon the casing, substantially as and for the purpose set forth.
- 45 2. In a signal-torch, the combination with a casing having a longitudinal exterior groove, and containing an inflammable material, of an igniting device embedded within the inflammable material and projecting into the

groove, and a cap having an inner rib provided with a roughened or friction surface, said rib registering with the groove in the casing, and the roughened or friction surface thereof adapted to light the igniting device, substantially as shown and described.

3. In a signal-torch, the combination with a casing having longitudinal external grooves, provided at their outer ends with slots communicating with the interior of the casing, and an inflammable material contained within the latter, of matches or the like embedded in the inflammable material, and having their heads projecting through the respective slots and received within the adjacent grooves, and a cap having inner longitudinal ribs terminating short of the closed end of the cap, and provided with roughened or friction surfaces, said cap being slidably fitted to the casing, and the ribs registering with the respective grooves thereof, substantially as and for the purpose set forth.

4. In a signal-torch, the combination with a tubular casing formed of paper or like light material, having longitudinal grooves pressed in the outer side thereof, and containing an inflammable material, of igniting devices embedded within the inflammable material and projecting into the respective grooves, and a tubular cap formed of material similar to the casing, and having external grooves pressed therein and forming inner ribs, the latter being provided with roughened or friction surfaces, the cap being slidably fitted to the casing, and the ribs registering with the grooves thereof, substantially as and for the purpose set forth.

5. A signal-torch, comprising a casing, containing an inflammable material, and an igniting device embedded in said inflammable material and projecting beyond a side of the casing, and a cap slidably fitted upon the casing, and provided with an inner roughened or friction surface, said casing and cap having registering ribs and grooves for preventing axial turning of the cap upon the casing, substantially as shown and described.

In testimony that I claim the foregoing as my own I have hereto affixed my signature in the presence of two witnesses.

OSCAR V. WOOD.
